Primary Examiner—A. Hugo Word*Assistant Examiner*—Doris V. Coles**[57] CLAIM**

The ornamental design for a fishing rod handle, as shown and described.

DESCRIPTION

FIG. 1 is a perspective view of a fishing rod handle showing my new design; The broken line showing of part of a fishing rod is for illustrative purposes only and forms no part of claimed design;
FIG. 2 is an enlarged left side elevational view thereof;
FIG. 3 is a front elevational view thereof;
FIG. 4 is a rear elevational view thereof;
FIG. 5 is a right side elevational view thereof; and,
FIG. 6 is a bottom plan view thereof.

FIG. 6

FIG. 2

FIG. 3

FIG. 4

FIG. 5
